UNITED STATES PATENT OFFICE.

EMMET F. CRIDER, OF COLUMBUS GROVE, OHIO.

DESIGN FOR A BUCKLE.

SPECIFICATION forming part of **Design No. 20,861**, dated **June 23, 1891**.

Application filed May 25, 1891. Serial No. 394,061. Term of patent 14 years.

To all whom it may concern:

Be it known that I, EMMET F. CRIDER, a citizen of the United States, residing at Columbus Grove, in the county of Putnam and State of Ohio, have invented and produced a new and original Design for Buckles; and I do hereby declare the following to be a full, clear, and exact description of the same, reference being had to the accompanying drawings, forming a part thereof.

In the annexed drawings, Figure 1 represents a vertical longitudinal sectional view of the buckle, showing my design and taken on line *y y*, Fig. 2. Fig. 2 is a vertical transverse sectional view of the same, taken on line *x x*, Fig. 1, and Fig. 3 is a perspective view of the same, these three views being deemed necessary to fully illustrate my design.

The leading features of my design consist in a broad raised plate, the outlines of which, when viewed in cross-section, as shown in Fig. 2, present a curved surface, the outer por-

tions or sides being rounded and terminating with the side bars clearly shown in Fig. 2 of the drawings.

²⁵ A is the broad curved plate. B B are straight end bars, and with the broad plate connect the two side bars C C to one another. A tongue pivoted on one of the bars B B is shown, and a notch is represented in the plate. ³⁰ These side bars are curved from end to end. The contour presents a raised horizontal curvature, as well as a transverse, curved, and sloping broad plate.

What I claim is—

³⁵ The design for a buckle herein shown and described.

In testimony whereof I affix my signature in presence of two witnesses.

EMMET F. CRIDER.
